UNITED STATES PATENT OFFICE.

CLIFFORD W. MARSH, OF BRIDGEPORT, CONNECTICUT.

TYPEWRITING MACHINE.

1,417,472.

Specification of Letters Patent. Patented May 23, 1922.

Application filed March 11, 1921. Serial No. 451,611.

To all whom it may concern:

Be it known that I, CLIFFORD W. MARSH, a citizen of the United States, residing at Bridgeport, county of Fairfield, State of Connecticut, have invented an Improvement 5 in Typewriting Machines, of which the following is a specification.

This invention relates to typewriting or similar mechanism for filling out forms and 10 simultaneously making manifold copies thereof, as, for example, in making out insurance policies by filling in the necessary data in spaces provided in printed blanks, the original of each policy being delivered 15 to the party insured, and one or more copies thereof being preserved in the files of the insurance company.

In work of this character it is customary to provide a considerable number of different 20 forms to correspond with the different kinds of policies written, a separate form being used for each type of policy, and each individual policy being prepared by writing into the proper form the appropriate data 25 in accordance with the facts. The usual operation involves selecting from the filing case in which the form blanks are stored, the required number of copies of the proper form blank assembling these blanks with the 30 necessary number of carbon sheets, and inserting and positioning the assembled blanks and carbon sheets in the typewriter, all of which must be done before the work of filling in the forms is commenced, thereby consuming 35 in preparation for the work, a considerable amount of time in proportion to the time needed for the actual making out of the forms.

The present invention has for its primary 40 object the provision of means whereby this loss of time may be greatly reduced and the required number of duplicate copies prepared in accordance with any desired stock form, with a minimum expenditure of time 45 and effort.

A more particular object of the invention is to provide means whereby a considerable stock of blanks for each of a number of different forms may be conveniently stored and 50 rendered quickly available for the purpose of preparing the required number of copies of a policy or other document from any said forms.

Further objects of the invention are to provide means for facilitating the introduction 55 of the required blanks into the proper writ-

ing position with reference to a typewriter and for eliminating the necessity of excessive care on the part of the operator in order to insure the proper manipulation and operation of the mechanism.

With the foregoing and other objects in view I have devised the novel mechanism which I will now describe, reference being had to the accompanying drawing, in which:

Fig. 1 is a side elevation of the complete apparatus, the side wall of the cabinet being partly broken away to show the interior construction and arrangement.

Fig. 2 is a vertical section taken substantially on the line 2—2 Fig. 1.

Fig. 3 is a horizontal section taken substantially on the line 3—3, Fig. 1.

Fig. 4 is a detail elevation, looking from the line 4—4, Fig. 2, of the mechanism for locking the elevator, one of the carriers being shown in section.

Fig. 5 is a perspective view of the typewriter, showing one of the carriers in writing position therein.

Fig. 6 is a similar view with the carrier removed.

Fig. 7 is an enlarged plan view of the rear portion of the typewriter, showing the construction of the carriage.

Fig. 8 is a detail sectional view, taken substantially on the line 8—8, Fig. 7, of the locking device for the typewriter carriage.

Fig. 9 is a plan view, Fig. 10 a side elevation, and Fig. 11 a front elevation of one 90 of the carriers.

Fig. 12 is an enlarged fragmentary plan view, partly in section, showing the mechanism for feeding the carbon strips or webs.

Fig. 13 is a detail perspective view of the 95 rear end of the carrier.

Fig. 14 is a detail side elevation of the front end of the carrier, looking from the right in Fig. 11.

Fig. 15 is a detail elevation, as viewed from 100 the line 15—15, Fig. 12, of the rollers for feeding the carbon strips.

Fig. 16 is a detail section taken substantially on the line 16, Fig. 15.

Fig. 17 is a longitudinal vertical section, 105 taken substantially on the line 17—17, Fig. 9, of the carrier, showing the parts in operative position.

Fig. 18 is a similar view, showing the feed rollers separated and the actuating mechanism for the reels disconnected from the latter.

Fig. 19 is a transverse section taken substantially on the line 19—19, Fig. 17.

Fig. 20 is a detail section, on the line 20—20, Fig. 19, of the means for frictionally connecting the reels with their operating gears.

Fig. 21 is an enlarged detail section on the line 21—21, Fig. 9.

Fig. 22 is a considerably enlarged detail section of the platen, showing the work sheets, transfer webs and guard strips.

Referring to Figs. 1, 5, 6 and 7, 25 denotes a typewriting machine having the usual type keys 26, shift keys 27, space bar 28, type bars 29, and ribbon feed mechanism 30. Said typewriting machine may, in general, be of any usual or well known form with the exception of the carriage and the supporting means therefor, which are of 20 special construction as will now be described.

31 denotes brackets bolted or otherwise secured to the rear of the typewriter frame and supporting parallel front and rear rails 32 and 33 upon which the rearwardly elongated carriage is supported, as by rollers 34, for travel transversely of the typewriter frame. Although the carriage and its supporting means are of novel construction, the means for operating said carriage may be of 25 well known form comprising the usual tension mechanism 35, (Fig. 7) and escapement mechanism 36, the latter including a pinion (not shown) on the typewriter frame, said pinion engaging a rack 37 on the carriage, as will be familiar to those skilled in the art without illustration or description in detail. The escapement mechanism is, as usual, manually operable to release the carriage by means of an escapement release bar 39 operable by finger levers 40 whenever it is desired to move the carriage by hand. Said carriage comprises a rectangular frame formed of rearwardly extending rails 41 and transverse front and rear bars 42 and 43, 40 respectively, connecting the rails 41 and carrying the rollers 34. The travel of the carriage in opposite directions is limited by engagement of a lug 44 carried by the bar 42 with studs 45 on the rail 32. In view of the 45 weight of the carriage and the parts (hereinafter described) supported thereby, there is preferably provided, for the purpose of returning said carriage at the end of its stroke, an enlarged plate or disc 46 in lieu of the usual carriage return and paper feed lever, said plate being supported from one of the rails 41 by a bracket 47, and being adapted for engagement by the palm of the operator's hand in order to force the carriage back against the pull of the tension mechanism 35.

The carriage above described is adapted to receive any one of a plurality of interchangeable carriers 48 which are identical 50 in construction. Each of the said carriers

comprises a shallow, trough-like frame 49 (see particularly Figs. 17, 18 and 19) reinforced at its rear end by a cross member 50 and at its forward end by an upper transverse bar 51, said member and bar being 70 provided with handles 52 and 53 by which the carrier may be readily lifted and otherwise manipulated. Each of the carriers 48 further comprises a platen 54 adapted, when the carrier is in operative or writing position 75 in the carriage, to receive the impression of the type on the type bars 29 (see particularly Fig. 21) and carries a suitable number of work sheet reels 55 which carry the work sheets or blank forms which are to be filled 80 out. Said blank forms are printed in series on continuous paper webs 56 which are wound on the reels and are of considerable length, the webs carried by all of the reels 55 of the same carrier being similarly printed 85 to constitute like forms, and the several carriers being provided with differently printed webs in accordance with the different forms in use, it being understood that a number of carriers corresponding to the number of 90 forms used will be employed. As hereafter more fully described, means are provided for feeding the webs 56 from the several reels 55 over the platen 54 in superposed relation and for passing between said webs a suitable 95 number of strips or webs 57 of carbon paper or equivalent transfer or manifolding material, whereby all of said webs may receive the same impressions from the type-bars 29 during their passage over the platen.

100 The carriage as above described is of special construction and has a function different than that of the usual typewriter carriage. It is means by which the carrier units, comprising the platen, work sheets and carbon paper or transfer material, are removably connected with the reciprocating mechanism of the typewriter which includes the tension and escapement mechanism.

105 Said means, while described as a carriage and illustrated as a frame, may be of any construction adapted to allow the operator to quickly and easily bring the carrier units into connection with and disconnect them from said reciprocating mechanism, thereby 110 making the carrier units freely interchangeable and differentiating from the practically permanent connection now employed. The connection or relation between the units and the reciprocating mechanism is such 115 that the units may be disconnected and removed therefrom without breaking down the reciprocating mechanism. In short in applicant's device the carrier units are freely interchangeable, and one may be removed 120 from the typewriter and another placed in position thereon without breaking down any part of the typewriter or carrier, or changing either one in any way.

125 Each carrier frame 49 is secured to and 130

- supported by a pair of cross bars 58 provided at their ends with rollers 59 (see Figs. 9 and 10) adapted to travel on the carriage rails 41, said bars 49 having end 5 extensions or lugs 60 adapted to enter notches 61 (see Fig. 7) formed in inwardly projecting flanges 62 at the upper sides of said rails 41. In order to place any carrier 48 in operative position in the typewriter carriage, the lugs 60 of the carrier in question are dropped through the notches 61 of the carriage rails 41, thereby seating the rollers 59 on said rail, and the carrier moved 10 forwardly along said rails into writing position with the platen 54 so located as to receive the impression of the type faces on the type-bars 29, this forward movement of the carrier bringing the lugs 60 beneath the flanges 62 and thereby retaining said carrier 15 in place on the carriage. In order to facilitate the placing of the carrier on the carriage the rails 41 may, if desired, be provided with outwardly flared guide members 63 (see Figs. 5 and 6) adapted to guide the 20 rollers 59 into position on said rails, one of said guide members 63 being provided with forwardly and rearwardly flared guide flanges 64 adapted to guide one of the lugs 60 into the corresponding notch 61. The 25 forward movement of the carrier on the carriage is limited, in order properly to position the platen with respect to the type bars, by means of an adjustable stop screw 65 carried by the transverse bar 43 of the carriage and adapted to engage a lug 66 (see Fig. 10) on one of the cross bars 58. Said carrier is locked in the writing position, after being brought thereinto, by means of a 30 locking dog 67 pivoted to a bracket 68 secured to one of the rails 41 and normally held by a spring 69 in an elevated position to engage a lug 70 (see Fig. 10) on the bottom of the carrier frame 49, said dog being depressed to release the lug 70 and permit 35 the rearward movement and removal of the carrier by means of a lever 71 pivoted at 72 to one of the side members of the carrier frame 49 and provided with an operating finger piece 73.
- 40 Means are preferably provided for preventing the insertion of a carrier into the carriage or the removal of the same therefrom except when said carriage is in its extreme position toward the right (i. e. in a 45 position to begin a line of writing) and also to prevent the movement of the carriage, and consequently the operation of the typewriting mechanism, until the carrier has been moved into the proper writing position.
- 50 To these ends, in the construction shown, the following devices are provided.
- 55 74 (Figs. 6 and 7) denotes a cam bar comprising an upwardly offset, longitudinally tapering flange on the rear carriage rail 33.
- 60 75 (see Figs. 12 and 13) denotes a down- 65 wardly projecting lug on a bracket 76 riveted or otherwise secured to the bottom of the carrier frame 49. The lug 75 is so positioned that, when the carriage is in its extreme position toward the right, it will just clear the inner end of the flange 74 when the lugs 60 are inserted in the notches 61, and when the carrier is moved forwardly into the writing position will just clear the forward edge of said flange. When, however, the carriage is in any other position, engagement of said lug with said flange will prevent lowering of the carrier to a sufficient extent to pass the lugs 60 downwardly through the notches 61, or, if the carrier be already in place on carriage, will prevent rearward movement of said carrier to a sufficient extent to permit said lugs to be freed from said notches.
- 70 77 (Figs. 7 and 8) denotes a locking dog 75 pivoted at 78 in a knob cut in the forward cross bar 42 of the carriage near one of the rails 41, said dog being adapted, when said carriage is in its extreme position towards the right, to engage a notch 79 in the rail 32, thereby locking said carriage against movement, said dog being moved into engagement with said notch by means of a spring 80. The dog 77 is formed with an extended upper end 81 which, when said dog is in locking engagement with the notch 79, projects slightly above the top of the adjacent rail 41, so that when a carrier 48 is moved into writing position one of the rollers 59 thereof will engage and depress the end 81 of the dog 77, lifting the latter out of the notch 79 and unlocking the carriage.
- 75 80 Each of the reels 55 comprises a hollow core provided with end flanges and mounted on an arbor 82 (see Fig. 19) having a reduced end 83 received in a suitably disposed socket or opening in one of the side members of the carrier frame 49 and a flattened end 84 which is detachably seated in a slot or notch formed in the upper edge of the opposite side member of said frame. The arbor 82 is of less diameter than the hollow core of the reel 55 and carries at one end a hub 85 which enters one end of said hollow core and is frictionally connected therewith by a spring 86 (see also Fig. 20) secured to said hub and bearing against the inner surface of said core. At the opposite end of the core 85 is a second hub 87 having a wedge shaped key 88 which enters a notch in the end of the reel, said hub being held in engagement with the reel by a collar 89 fast upon the arbor 82 by means of a set screw 90. The collar 89 and hub 87 are longitudinally adjustable on the arbor 82 in order to cooperate with 90 reels of different lengths carrying work sheet webs of different widths.
- 95 90 The platen 54 comprises a flat bar of any suitable composition usually employed for this purpose, said bar being mounted in a 100
- 105 100
- 110 110
- 115 115
- 120 120
- 125 125
- 130 130

channel member 91 (Figs. 21 and 22) supported at its ends by brackets 92 secured to the side members of the carrier frame 49. 93 denotes guide rods or rollers supported 5 at their ends by the brackets 92 and disposed parallel to the platen bar 54 above and below the same for guiding the webs across the flat impression face of said platen bar. 94 denotes guide fingers carried by the channel 10 member 91 and between which and a guide plate 95 (Figs. 6 and 7) on the carriage the webs 56 are guided to the lower guide roller 93.

96 and 97 denote upper and lower feed 15 rollers to which the webs pass after leaving the upper guide roller 93, said rollers being preferably connected by gears 99 (Fig. 11). The upper feed roller 96 is journalled in arms 98 (see Figs. 17 and 18) pivoted at 100 20 to the side members of the carrier frame 49, said arms being normally depressed to force the feed roller 96 against the feed roller 97 by means of springs 101 connected at their lower ends to the bottom of the carrier 25 frame and at their upper ends to saddles 102 having abutment screws 103 engaging said arms 98, whereby the effective tension of said springs may be adjusted. The arms 98 may be raised against the tension of the 30 springs 101 to separate the feed rollers (as shown in Fig. 18) by means of cam surfaces on a shaft 104 journalled in the side members of the carrier frame and provided outside said frame with an operating handle 35 or finger piece 105. The lower feed roller 97 is journalled in the side members of the carrier frame and is provided outside said frame with operating knobs 106 (Figs. 9 and 11) and with a star wheel 107 (Fig. 14) 40 cooperating with a roller 108 carried by a spring depressed arm 109 in order to provide the usual line positioning of the feed rollers, said roller 108 being movable out of engagement with the star wheel 107 by 45 means of a cam disc 110 rotatably mounted on the journal of the roller 96 and provided with a finger piece 111.

The feed roller 97 is preferably cut away 50 to form isolated feeding discs 112 cooperat- 55 ing with the roller 96 and between which project portions of a guide plate 113, whereby the webs are guided from the feed rollers out of the carrier and past the edge of a tear-off knife 114 (Figs. 9 and 21) carried by 58 the bar 51.

Referring to Fig. 11, 115 denotes a worm gear loosely mounted on the feed roller 97 and provided with ratchet teeth which cooperate with complementary ratchet teeth 60 formed on the corresponding gear 99, said worm gear 115 being pressed toward the gear 99 by a spring 116, and the construction being such that, when the roller 97 is turned in the direction to advance the webs, the gear 99 is permitted to turn idly with respect 65 to the gear 115, but when said roller is turned in the opposite direction the gear 115 will be operatively connected with the gear 99 for rotation therewith. The gear 115 meshes with a worm 117 (Figs. 17 and 18) on a longitudinal shaft 118 loosely journalled at its forward end in one of the brackets 92 and at its rear end in a flange 126 on a slide 119 connected with one of the side members of the carrier frame for limited vertical movement 70 thereon, as by means of studs 120 projecting from said slide and working in slots 121 in said side member. The shaft 118 carries a series of worms which cooperate with worm gears formed on the hubs 85. 124 denotes a rod disposed parallel to the shaft 118 and guided for longitudinal movement on the bottom of the carrier frame, said rod having at its rear end a spring cam member 125 adapted, when said rod is in its forward position, to engage the flange 126 and hold the slide 119 in its elevated position with the worms 122 in mesh with the worm 80 gears 123. At its forward end the rod 124 is provided with a pair of lugs 127 and 128 85 adapted to receive between them an arm 129 on the cam shaft 104. The construction is such that, when the finger piece 105 is operated to separate the feed rollers 96 and 97, engagement of the arm 129 with the lug 128 90 will move the rod 124 rearwardly into the position shown in Fig. 18, permitting the slide 119 and shaft 118 to drop and thereby carrying the worm 122 out of engagement with the worm gears 123. When, however, 95 the finger piece 105 is returned to its normal position, as shown in Fig. 17, engagement of the arm 129 with the lug 127 will move the rod 124 forwardly, thereby causing the spring cam 125 to raise the slide 119 and 100 engage the worms 122 with the gears 123.

From the foregoing it will be seen that when the feed roller 97 is turned by either of the knobs 106 to move the paper webs backwardly or downwardly the reels 55 will 105 be positively actuated to wind up the amount of web thus fed backwardly by the feed rollers, but that when said feed rollers are operated in the usual manner to advance the web, the reels will not be positively actuated 115 but will be turned merely by the withdrawal of the web therefrom. It will also be seen that when the feed rollers are separated, for the purpose of positioning the web therebetween or otherwise, the actuating mechanism for the reels will be disconnected so as not to interfere with the free manipulation of the web as may be desired. It will furthermore be seen that the connection between each of the reels and its actuating 120 means is a yielding or frictional one through the hub 85 and spring 86, thereby avoiding injury to the web by overactuation of any 125

reel by reason of inequalities in the amount of web wound on the several reels or otherwise.

The carbon paper or other transfer material is preferably also supplied in the form of a suitable number of continuous strips or webs 57, said webs being stored in the form of rolls wound on studs 130 (Figs. 9 and 10) having flattened or notched portions which 10 are received in slots or notches 131 (see Figs. 17 and 18) in one of the side members of the carrier frame 49. Withdrawal of the transfer webs from the rolls is yieldingly resisted, so as to apply a light tension to said webs, 15 by means of discs 132 loosely mounted on reduced outer ends of the studs 130 and pressed into engagement with the outer faces of the rolls by means of springs 133 interposed between said discs and adjusting nuts 20 on the outer ends of said studs. From the rolls the transfer web is carried about suitable guide studs or members 135, 136 and 137, thence longitudinally of the platen bar 54 between the work sheet webs 56 and trans- 25 verse to the latter, and finally about a guide 138 (Fig. 11) at the opposite side of frame to mechanism for periodically feeding said webs a predetermined amount in order to supply fresh portions thereof at the point 30 where the writing takes place. Referring to Figs. 12, 15 and 16, 139 denotes a short upright shaft journalled in a bracket 140 secured to one of the side members of the carrier frame 149 and having fast thereon a 35 feed roller 141. 142 denotes a cooperating feed roller journalled on an eccentric stud 143 rotatably mounted in the bracket 140 and provided with a finger piece 144 whereby said stud may be turned to separate the 40 feed rollers. 145 denotes a pinion loosely mounted on the shaft 139 and provided with spring pressed pawls 146 which engage internal ratchet teeth in the walls of a concentric recess formed in the upper end of the 45 roller 141. By this construction it will be seen that the feed roller 141 may be turned by the pinion 145 or independently thereof by the shaft 139 which is preferably provided with a manual operating knob 147. 50 The pinion 145 meshes with a rack 148 formed on the forward end of a link 149 connected with the adjacent side member of the carrier frame by a spring 150. The rear end of the link 149 is formed with an ear 55 pivoted at 151 (see Figs. 12 and 13) to a lever 152 fulcrumed at 153 to the bottom of the carrier casing and having at its opposite end a stud 154 guided in a slot in the bracket 76 and adapted to engage the inclined edge 60 of the cam flange 74. The construction is such that, as the carriage is moved from left to right in order to commence a new line of writing, engagement of the stud 154 with the cam flange 74 will rock the lever 152 on its pivot, moving the link 149 in opposition

to the spring 150, thereby, through the rack 148, pinion 145, and pawls 146, turning the feed roller 141 and advancing the transfer web a predetermined amount. As the carriage travels from right to left during the 70 writing operation the cam flange 74 permits the spring 150 to return the link 149 to its initial position, the pinion 145 at this time turning idly without moving the feed roller 141. In order to permit the effective stroke 75 of the lever 152 to be varied, thereby varying the amount which the transfer web is fed at each traverse of the carriage, the pivot 153 comprises a stud which is received in a slot 155 in said lever and is carried by a slide 156 80 adjustably connected with the back member 50 of the carrier frame by a screw 157 working in a slot 158 in said frame member. It will be seen that with this construction the fulcrum of the lever 152 may be adjusted, 85 thereby varying the stroke of the link 149.

As is common practice in typewriter construction, each type bar 29 is provided with two type faces 159 and 160 (Fig. 21) which are brought alternatively into printing position by operation of the shift keys 27. In order to avoid all possibility of a double impression of these two type faces, due to the flat surface of the platen 54, as also to hold the webs 56 (which are slightly curved by reason of their having been rolled on the reels 55) in flat position against the impression surface of the platen, the following devices are preferably employed. 161 (Figs. 10, 11, 14 and 21) denotes plates having projecting lugs 162 which are received in apertures in the brackets 92. The plates 161 are connected by spaced, parallel guard strips 163 (see particularly Figs. 11 and 22) 90 preferably composed of a slightly elastic textile material, the elasticity of said strips holding the plates 161 with their lugs 162 in engagement with the apertures in the brackets 92, and said plates holding said strips stretched across the webs 56 in such 100 a manner as to hold the latter tightly against the platen 54. The spacing of the strips 163 corresponds approximately with the width of a single line of writing, thereby making it impossible to obtain a double 105 impression from the type faces 159 and 160. 110

In order conveniently to store a suitable number of carriers 48 with their respective different forms of work sheets and to render any of said carriers readily accessible for the 120 purpose of introduction into the typewriting machine, the following means are preferably employed, reference being had to Figs. 1 to 4.

164 denotes a cabinet preferably provided at its forward side with a shelf 165 for supporting the typewriter 25. Within the cabinet 164 is a pair of vertically disposed uprights 166 constituting guides for a carrier holder or elevator comprising up- 125 130

- rights 167, cross members 168, and braces 169. Said elevator is movable upwardly through an opening in the top of the casting 164, which opening is closed, when the 5 elevator is depressed, by a cover 170 carried by the upper ends of the uprights 167. 171 denotes weights guided by uprights 172 and connected by chains 173 passing over pulleys 174 and 175 with brackets 176 secured 10 to the bottom of the elevator, said weights serving as a counterpoise for said elevator. For raising and lowering the elevator there is provided a hand lever 177 mounted on a shaft 178 journaled in the frame of the 15 cabinet and having fast thereon a bail 179 connected by a link 180 with a bracket 181 secured to one of the elevator cross members 168.
- Adjacent their upper ends the elevator 20 uprights 167 carry a plurality of pairs of horizontally disposed rails 182 connected at their forward ends by upright bars 202, said rails being vertically spaced a sufficient distance to receive between them the carriers 25 48, so as to constitute compartments for said carriers and horizontally spaced to correspond with the horizontal spacing of the carrier rails 41 of the typewriter carriage. Each pair of rails 182 is adapted to receive 30 and support one of the carriers 148, inward movement of said carriers along said rails being limited by stops 183 which engage the rear carrier rollers 59. The construction is such that any pair of rails 182 may be 35 brought into alinement with the rails 41 of the typewriter carriage when the latter is in its position farthest toward the right, thereby permitting a carrier 48 to be run from the rails 182 to the rails 41, and vice versa.
- 40 In order to assist the operator in positioning the carrier holder or elevator with any given pair of rails 182 in accurate alinement with the rails 41, one of the elevator uprights 167 is formed with a series 45 of beveled notches 184 adapted to receive the beveled end of a positioning dog 185 pivoted to one of the guides 166 and controlled by a spring 186 which tends to force said dog into engagement with said notches.
- 50 The notches 184 are so located that when any is engaged by the dog 185 one of the pairs of rails 182 will be in accurate alinement with the rails 41, the beveled shape of said notches and dog causing the elevator 55 to be automatically moved into this position when manually brought nearly thereinto. For releasing the dog 185 there is provided a treadle 187 in the form of a bell crank lever pivoted to the cabinet frame adjacent the bottom of the latter and connected by a chain 188 with a bell crank lever 189 also pivoted to the cabinet frame and connected by a chain 190 with a bell crank lever 191 pivoted to one of the up-
- rights 166 and connected by a chain 192 65 with the dog 185.
- For locking the several carriers 48 against accidental displacement from their respective rails 182 except when said rails are in alinement with the rails 41, there are provided spring actuated locking dogs 193 (Fig. 1) respectively adapted, when in normal position, to engage one of the lugs 60 of each of the several carriers to hold the latter against forward movement. Each of the 75 locking dogs 193 is provided with an arm 194 having a stud 195 which cooperates with a fixed cam plate 196 carried by the upper end of one of the uprights 166. As each pair of rails 182 is brought into alinement with 80 the rails 41 the stud 195 on the corresponding locking dog 193 is brought into engagement with the cam plate 196, thereby rocking said dog and moving it out of engagement with the lug 60, so as to permit the forward movement of the corresponding carrier 85 48 from the rails 182 to the rails 41.
- It is, of course, important that the elevator be not moved when any carrier 48 has been moved partly but not entirely out of 90 said elevator so as to be supported partly by the rails 182 and partly by the rails 41. In order to prevent such accidental movement of the elevator the following mechanism is employed. 197 (Figs. 2 and 4) denotes a dog pivoted to one of the elevator uprights 167 and adapted to engage any one of a series of notches 198 in the corresponding upright 166 when any pair of rails 182 is in alinement with the 100 rails 41, thereby locking the elevator against vertical movement. The dog 197 is connected by a link 199 with a series of levers 200 pivoted to one of the elevator uprights 167 and having at their forward ends projections 201 adapted for engagement by the bottoms of the carrier frames 49 as the carriers are moved into and out of the elevator. Normally the projections 201 extend slightly above the tops of the rails 182, and the locking dog 197 is out of engagement with any of the notches 198, this being the condition when all of the carriers 48 in the elevator are moved fully back therein, as shown in Fig. 1 and at the top in Fig. 4. When, however, 115 any carrier is moved outwardly from the rails 182 upon the rails 41, engagement thereof with the projection 201 on the corresponding lever 200 will cause the latter to raise the link 199 and move the dog 197 into 120 locking engagement with one of the notches 198 until the carrier has been moved entirely out of the elevator and out of engagement with said lever. When the carrier is returned to the elevator the projection 201 125 is again engaged and the lever 200 held depressed, thereby again locking the elevator until the carrier has been fully returned.

It will be understood that when the carrier holder or elevator last described is employed, the guide members 63, shown in Figs. 5 and 6, may be omitted, as may also 5 the notches 61 in the flanges 62 of the rails 41.

In operation, when it is desired to prepare a document based upon a given form, the operator will first depress the treadle, there- 10 by removing the positioning dog 185, and will then operate the lever 177 to bring the carrier 48 containing the desired form into a position opposite the typewriter carriage, which at this time has been moved to its ex- 15 treme position toward the right. The treadle 187 is then released permitting the positioning dog 185 to bring the rails 182 into accurate alinement with the rails 41. At the same time, the cam plate 196 will have 20 depressed the proper locking dog 193 to release the desired carrier. The handle 53 of said carrier is then grasped and the carrier drawn forwardly from the elevator rails 182 upon the carriage rails 41, until the lug 66 25 thereon engages the stop screw 65, thereby bringing said carrier to the writing position in which it is locked by the dog 67. The knobs 106 are then turned to bring the blank spaces successively opposite the platen, and 30 the desired data filled in, in the usual manner, by the typewriter, the successive return movements of the carriage operating through the cam flange 74, lever 152 and link 149 to feed the transfer webs 57 forwardly a pre- 35 determined amount for each line that is written. When a set of forms has been completely filled out, the knob 106 is further turned to bring the bottom edges of said blanks opposite the edge of the tear-off knife 40 114, whereupon the completed documents may be detached, leaving the webs in position to commence the immediate preparation of another document of the same form. If another form is next required, the finger 45 piece 73 is manipulated to release the dog 67 (the typewriter carriage having been re-turned to its initial position farthest to the right) and the carrier 48 moved backwardly upon the elevator rails 182. Thereafter the 50 treadle 187 is again depressed to release the positioning dog 185 and the lever 177 again manipulated to bring another carrier 48 in position opposite the typewriter, these operations being repeated from time to time 55 in accordance with the requirements.

From the foregoing it will be seen that an assembled set of any desired forms can at will be easily and quickly brought into position to be filled out by the typewriter with- 60 out the usual delays, the various safety or locking devices above described making it virtually impossible to operate the mechanism in an improper manner, thereby relieving the operator of all necessity of exer- 65 cising special care in order to prevent such

improper operation and eliminating the necessity of special skill in using the apparatus.

Having thus described my invention I claim—

1. The combination with the printing de- 70 vices of a typewriter having a reciprocating mechanism, of a carrier comprising in combination as a unit, a platen, work sheets and transfer material; and means to removably connect said carrier unit with said reciprocating mechanism.

2. The combination with the printing de- 80 vices of a typewriter having a reciprocating mechanism, of a carrier comprising in combination as a unit, a platen, means for carrying work sheets and means for carrying transfer material; and means to removably connect said carrier unit with said reciprocating mechanism.

3. The combination with the printing de- 85 vices of a typewriter having a reciprocating mechanism, of a carrier comprising in combination as a unit, a platen, work sheets with means for positioning the same upon said platen, and transfer material with means for interposing the same between said work sheets when the latter are opposite said platen; and means to removably connect said carrier unit with said reciprocating mech- 90

anism.

4. The combination with the printing de- 100 vices of a typewriter having a reciprocating mechanism, of a carrier comprising in combination as a unit, a platen, work sheets with means for positioning the same upon said platen, and one or more transfer webs with means for feeding the same between said work sheets in a direction transverse to the direction of the feed of the latter when said 105 work sheets are opposite said platen; and means to removably connect said carrier unit with said reciprocating mechanism.

5. The combination with the printing de- 110 vices of a typewriter having a reciprocating mechanism, of a carrier comprising in combination as a unit, a platen, means for carrying a supply of work sheets and positioning the same upon said platen, means for carrying a supply of transfer material and inter- 115 posing the same between said work sheets when the latter are opposite said platen; and means to removably connect said carrier unit with said reciprocating mechanism.

6. The combination with the printing de- 120 vices of a typewriter having a reciprocating mechanism, of a carrier comprising in combination as a unit, a platen, work sheets, and transfer material; and means to removably connect said carrier unit with said reciprocating mechanism and allow it to be disconnected therefrom while the reciprocating mechanism remains intact.

7. The combination with the printing de- 130 vices of a typewriter having a reciprocating

- mechanism of a carrier comprising in combination as a unit, a platen, means for carrying work sheets, and means for carrying transfer material; and means to removably connect said carrier unit with said reciprocating mechanism and allow it to be disconnected therefrom while the reciprocating mechanism remains intact.
8. The combination with the printing devices of a typewriter having a reciprocating mechanism, of a carrier comprising in combination as a unit, a platen, work sheets with means for positioning the same upon said platen, and transfer material with means for interposing the same between said work sheets when the latter are opposite said platen; and means to removably connect said carrier unit with said reciprocating mechanism and allow it to be disconnected therefrom while the reciprocating mechanism remains intact.
9. The combination with the printing devices of a typewriter having a reciprocating mechanism, of a carrier comprising in combination as a unit, a platen, work sheets with means for positioning the same upon said platen, and one or more transfer webs with means for feeding the same between said work sheets in a direction transverse to the direction of the feed of the latter when said work sheets are opposite said platen; and means to removably connect said carrier unit with said reciprocating mechanism and allow it to be disconnected therefrom while the reciprocating mechanism remains intact.
10. The combination with the printing devices of a typewriter having a reciprocating mechanism, of a carrier comprising in combination as a unit, a platen, means for carrying a supply of work sheets and positioning the same upon said platen, means for carrying a supply of transfer material and interposing the same between said work sheets when the latter are opposite said platen; and means to removably connect said carrier unit with said reciprocating mechanism and allow it to be disconnected therefrom while the reciprocating mechanism remains intact.
11. The combination with the printing devices of a typewriter having a carriage, of a carrier unit adapted to engage and disengage said carriage, and means on said carrier for carrying in combination as a unit, a platen, work sheets, and transfer material.
12. The combination with the printing devices of a typewriter having a carriage, of a carrier unit adapted to engage and disengage said carriage, and means on said carrier for carrying, in combination as a unit, a platen, work sheets with means for positioning the same upon said platen, and transfer material with means for interposing the same between said work sheets when the latter are opposite said platen.
13. The combination with the printing devices of a typewriter having a carriage, of a carrier unit adapted to engage and disengage said carriage, and means on said carrier for carrying, in combination as a unit, a platen, work sheets with means for positioning the same upon said platen, and one or more transfer webs with means for feeding the same between said work sheets in a direction transverse to the direction of the feed of the latter when said work sheets are opposite said platen.
14. The combination with the printing devices of a typewriter having a carriage, of a carrier unit adapted to engage and disengage said carriage, means on said carrier for carrying, in combination as a unit, a platen, means for carrying a supply of work sheets and positioning the same upon said platen, and means for carrying a supply of transfer material and interposing the same between said work sheets when the latter are opposite said platen.
15. The combination with the printing devices of a typewriter of a carrier adapted for attachment to and removal from a writing machine as a unit and comprising, in combination, a platen, a plurality of reels each adapted to hold a series of work sheets in the form of a continuous web, feed rollers for drawing said webs simultaneously from all of said reels, driving connections between said feed rollers and reels, and means for carrying a supply of transfer material and interposing the same between said webs.
16. The combination with the printing devices of a typewriter of a carrier adapted for attachment to and removal from a writing machine as a unit and comprising, in combination, a platen, a plurality of reels each adapted to hold a series of work sheets in the form of a continuous web, feed rollers operable in one direction for drawing said webs simultaneously from all of said reels, driving connections between said feed rollers and reels operable to turn said reels when said feed rollers are operated in the opposite direction, and means for carrying a supply of transfer material and interposing the same between said webs.
17. In a manifolding attachment for writing machines, a carrier adapted for attachment to and removal from a writing machine and comprising, in combination, a plurality of reels each adapted to hold a series of work sheets in the form of a continuous web, feed rollers for drawing said webs simultaneously from all of said reels, means for actuating said reels, a pair of cooperating ratchet clutch members connected respectively with one of said feed rollers and with said reel actuating means, and means for

carrying a supply of transfer material and interposing the same between said webs.

18. In a manifolding attachment for writing machines, a carrier adapted for attachment to and removal from a writing machine and comprising, in combination, a plurality of reels each adapted to hold a series of work sheets in the form of a continuous web, feed rollers for drawing said webs simultaneously from all of said reels, means for carrying a supply of transfer material and interposing the same between said webs, a worm gear carried by each of said reels, and a shaft operatively connected with one of said feed rollers and having a series of worms meshing with said worm gears respectively.

19. In a manifolding attachment for writing machines, a carrier adapted for attachment to and removal from a writing machine and comprising, in combination, a plurality of reels each adapted to hold a series of work sheets in the form of a continuous web, feed rollers for drawing said webs simultaneously from all of said reels, means for carrying a supply of transfer material and interposing the same between said webs, gears connecting said feed rollers, the gear on one of said rollers having a ratchet clutch face, a worm gear rotatably mounted on said last named feed roller and having a ratchet clutch face cooperating with said first named clutch face, a spring for forcing said clutch faces into engagement, worm gears carried by the several reels, and a shaft having a worm meshing with the worm gear on said feed roller and a series of worms meshing with the worm gears carried by the respective reels.

20. In a manifolding attachment for writing machines, a carrier adapted for attachment to and removal from a writing machine as a unit and comprising, in combination, a platen, a plurality of reels each adapted to hold a series of work sheets in the form of a continuous web, feed rollers for drawing said webs simultaneously from all of said reels, means for carrying a supply of transfer material and interposing the same between said webs, driving connections between said feed rollers and reels, and means for separating said feed rollers and for simultaneously disconnecting said driving connections.

21. In a manifolding attachment for writing machines, a carrier adapted for attachment to and removal from a writing machine and comprising, in combination, a plurality of reels each adapted to hold a series of work sheets in the form of a continuous web, feed rollers for drawing said webs simultaneously from all of said reels, means for carrying a supply of transfer material and interposing the same between said webs, a shaft operatively connected with one of said feed rollers and with each of said reels,

a support for said shaft movable to carry said shaft into and out of operative engagement with said reels, a longitudinally movable rod having a spring cam adapted to engage and move said support, a cam shaft for separating said feed rollers, and an arm on said shaft adapted to engage and move said rod when said shaft is turned in either direction.

22. In a manifolding attachment for writing machines, a carrier adapted for attachment to and removal from a writing machine and comprising, in combination, a plurality of reels each adapted to hold a series of work sheets in the form of a continuous web, feed rollers for drawing said webs simultaneously from all of said reels, means for carrying a supply of transfer material and interposing the same between said webs, a worm gear carried by each of said reels, a shaft operatively connected with one of said feed rollers and having a series of worms meshing with said worm gears respectively, a support for said shaft movable to carry said worms into and out of engagement with said worm gears, a longitudinally movable rod having a spring cam adapted to engage and move said support, a cam shaft for separating said feed rollers, and an arm on said shaft adapted to engage and move said rod when said shaft is turned in either direction.

23. In a manifolding attachment for writing machines, a carrier adapted for attachment to and removal from a writing machine as a unit and comprising, in combination, a platen, a plurality of reels each adapted to hold a series of work sheets in the form of a continuous web, feed rollers for drawing said webs simultaneously from all of said reels, means for carrying a supply of transfer material and interposing the same between said webs, and means operatively connected with said feed rollers and yieldingly connected with said reels respectively for rotating said reels.

24. In a manifolding attachment for writing machines, a carrier adapted for attachment to and removal from a writing machine as a unit and comprising, in combination, a platen, a plurality of reels each adapted to hold a series of work sheets in the form of a continuous web, means for carrying a supply of transfer material and interposing the same between said webs, feed rollers operable in one direction for drawing said web simultaneously from all of said reels, and means operatively connected with said feed rollers and yieldingly connected with said reels respectively for rotating said reels when said feed rollers are operated in the opposite direction.

25. In a manifolding attachment for writing machines, a carrier adapted for attachment to and removal from a writing ma-

- chine and comprising, in combination, a plurality of reels each adapted to hold a series of work sheets in the form of a continuous web, feed rollers for drawing said webs 5 simultaneously from all of said reels, means for carrying a supply of transfer material and interposing the same between said webs, worm gears having hubs frictionally connected with said reels respectively, and a 10 shaft operatively connected with one of said feed rollers and having worms meshing with the several worm gears.
26. In a writing apparatus, the combination with a typewriter having a transversely 15 movable carriage, of a carrier adapted for attachment to and removal from said carriage, a platen carried by the carrier, means on said carrier for carrying a supply of work sheets and for presenting the same in 20 writing position when said carrier is attached to said carriage, means on said carrier for feeding one or more continuous transfer webs between said work sheets and means operated by the transverse movements of said carriage for operating said 25 feeding means.
27. In a writing apparatus, the combination with a typewriter having a transversely 30 movable carriage and a stationary, longitudinally inclined cam member disposed substantially parallel to the direction of movement of said carriage, of a carrier adapted for attachment to and removal from said carriage, means on said carrier for carrying 35 a supply of work sheets and for presenting the same in writing position when said carrier is attached to said carriage, means on said carrier for feeding one or more continuous transfer webs between said work sheets, 40 and means cooperating with said cam member for operating said feeding means.
28. In a writing apparatus, the combination with a typewriter having a transversely 45 movable carriage and a stationary, longitudinally inclined cam member disposed substantially parallel to the direction of movement of said carriage, of a carrier adapted for attachment to and removal from said carriage, means on said carrier for carrying 50 a supply of work sheets and for presenting the same in writing position when said carrier is attached to said carriage, and means on said carrier for feeding one or more continuous transfer webs between said work 55 sheets, said feeding means comprising a pair of feed rollers, a pinion having a pawl and ratchet connection with one of said rollers, a link having a rack cooperating with said pinion, and a lever pivoted to said link and 60 having a stud engaging said cam member.
29. In a writing apparatus, the combination with a typewriter having a transversely 65 movable carriage and a stationary, longitudinally inclined cam member disposed substantially parallel to the direction of move- 70 ment of said carriage, of a carrier adapted for attachment to and removal from said carriage, means on said carrier for carrying a supply of work sheets and for presenting the same in writing position when said car- 75 rier is attached to said carriage, and means on said carrier for feeding one or more continuous transfer webs between said work sheets, said feeding means comprising a pair of feed rollers, a pinion having a pawl and ratchet connection with one of said rollers, a link having a rack cooperating with said pinion, a lever pivoted to said link and having a stud engaging said cam member, a 80 stud on which said lever is fulcrumed, said lever having a slot to receive said fulcrum stud, and a slide adjustably secured to said carrier and by which said fulcrum stud is carried.
30. In a manifolding attachment for writing machines, a carrier adapted for attachment to and removal from a writing machine as a unit and comprising, in combination, a platen, means for carrying a supply of work sheets and for presenting the same 85 in writing position when said carrier is attached to said writing machine, a stud on said carrier for supporting a roll of continuous transfer web, means for feeding said web between said work sheets when the latter are in writing position, a tension disc on said stud, and a spring for pressing said disc against said roll of transfer web.
31. In a writing apparatus, the combination with a typewriter having a carriage, of 90 a carrier adapted for attachment to and removal from said carriage, means on said carrier for carrying a supply of work sheets and for presenting said work sheets in writing position when said carrier is attached to 95 said carriage, a fixed bar disposed parallel to the direction of movement of said carriage, and a lug on said carrier adapted when said carriage is in one predetermined position to clear said bar and permit the attachment of said carrier to said carriage but to engage said bar and prevent such attachment when said carriage is in any other position.
32. In a writing apparatus, the combination with a typewriter having a transversely 100 movable carriage and a stationary, longitudinally inclined cam member disposed substantially parallel to the direction of movement of said carriage, of a carrier adapted 105 for attachment to and removal from said carriage, means on said carrier for carrying a supply of work sheets and for presenting the same in writing position when said carrier is attached to said carriage, means on 110 said carrier for feeding one or more continuous transfer webs between said work sheets, said feeding means comprising a pair of feed rollers, a pinion having a pawl and ratchet connection with one of said rollers, a link having a rack cooperating with said pinion, and a lever pivoted to said link and 115 having a stud engaging said cam member.
33. In a writing apparatus, the combination with a typewriter having a transversely 120 movable carriage and a stationary, longitudinally inclined cam member disposed substantially parallel to the direction of movement of said carriage, of a carrier adapted 125 for attachment to and removal from said carriage, means on said carrier for carrying a supply of work sheets and for presenting the same in writing position when said carrier is attached to said carriage, means on said carrier for feeding one or more continuous transfer webs between said work sheets, means cooperating with said cam member for operating said feeding means, and a lug on said carrier adapted when said 130

- carriage is in one predetermined position to clear said cam member and permit the attachment of said carrier to said carriage but to engage said cam member and prevent such attachment when said carriage is in any other position.
33. In a writing apparatus, the combination with a typewriter having a carriage, of a carrier adapted for attachment to and removal from said carriage, means for guiding said carrier into position on said carriage, means on said carrier for carrying a supply of work sheets and for presenting the same in writing position when said carrier is attached to said carriage, and means on said carrier for carrying a supply of transfer material and interposing the same between said work sheets when the latter are in writing position.
34. In a writing apparatus, the combination with a typewriter having a carriage, of a carrier adapted for attachment to and removal from said carriage, means for retaining said carrier in position on said carriage, means on said carrier for carrying a supply of work sheets and for presenting the same in writing position when said carrier is attached to said carriage, and means on said carrier for carrying a supply of transfer material and interposing the same between said work sheets when the latter are in writing position.
35. In a writing apparatus, the combination with a typewriter having type bars and a transversely movable carriage provided with a pair of parallel flanged rails disposed transverse to the direction of movement of said carriage, of a carrier having rollers to run on said rails and lugs to engage the flanges of said rails and retain said carrier in position thereon, and means on said carrier for carrying a supply of work sheets and transfer material and presenting the same in assembled relationship to the action of said type bars.
36. In a writing apparatus, the combination with a typewriter having type bars and a transversely movable carriage provided with a pair of parallel flanged rails disposed transverse to direction of movement of said carriage, said typewriter having also a fixed bar disposed parallel to the direction of movement of said carriage, of a carrier having rollers to run on said rail and lugs to engage the flanges of said rails and retain said carrier in position thereon, means on said carrier for carrying a supply of work sheets and presenting the same to the action of said type bars, and a lug on said carrier adapted when said carriage is in one predetermined position to clear said fixed bar and permit movement of said carrier on said rails but to engage said bar and prevent such movement when said carriage is in any other position.
37. In a writing apparatus, the combination with a typewriter having a carriage, of a carrier adapted for attachment to and removal from said carriage, means on said carrier for carrying a supply of work sheets and presenting the same to the writing mechanism of said typewriter, and means for preventing the removal of said carrier from said carriage except when said carriage is at the limit of its movement in one direction.
38. In a writing apparatus, the combination with a typewriter having a carriage, of a carrier adapted for attachment to and removal from said carriage, means on said carrier for carrying a supply of work sheets and presenting the same to the writing mechanism of said typewriter, and means for preventing the attachment of said carrier to said carriage or its removal therefrom except when said carriage is at the limit of its movement in one direction.
39. In a writing apparatus, the combination with a typewriter having a carriage, of a carrier adapted for attachment to and removal from said carriage and movable thereon into and out of writing position, means on said carrier for carrying a supply of work sheets and presenting the same to the writing mechanism of said typewriter when said carrier is in writing position, and means for positioning said carrier in writing position.
40. In a writing apparatus, the combination with a typewriter having a carriage provided with a bar disposed parallel to the direction of movement of said carriage and a stop screw carried by said bar, of a carrier movable on said carriage into and out of writing position, means on said carrier for carrying a supply of work sheets and presenting the same to the writing mechanism of said typewriter when said carrier is in writing position, and a lug on said carrier adapted to engage said stop screw and position said carrier on said carriage.
41. In a writing apparatus, the combination with a typewriter having a carriage, of a carrier movable on said carriage into and out of writing position, means on said carrier for carrying a supply of work sheets and presenting the same to the writing mechanism of said typewriter when said carrier is in writing position, and means for locking said carrier in writing position on said carriage.
42. In a writing apparatus, the combination with a typewriter having a carriage, of a carrier movable on said carriage into and out of writing position, means on said carrier for carrying a supply of work sheets and presenting the same to the writing mechanism of said typewriter when said carrier is in writing position, and a pivoted

- dog on said carriage adapted to engage said carrier and lock the same in writing position.
43. In a writing apparatus, the combination with a typewriter having a carriage, of a carrier movable on said carriage into and out of writing position, means on said carrier for carrying a supply of work sheets and presenting the same to the writing mechanism of said typewriter when said carrier is in writing position, and means for locking said carriage against movement until said carrier is moved into writing position.
44. In a writing apparatus, the combination with a typewriter having a carriage, of a carrier adapted for attachment to and removal from said carriage and movable thereon into and out of writing position, means on said carrier for carrying a supply of work sheets and presenting the same to the writing mechanism of said typewriter when said carrier is in writing position, means for preventing the attachment of said carrier to said carriage except when said carriage is at the limit of its movement in one direction, and means for locking said carriage against movement until said carrier is moved into writing position.
45. In a writing apparatus, the combination with a typewriter having a carriage and a notched rail on which said carriage runs, of a carrier movable on said carriage into and out of writing position, means on said carrier for carrying a supply of work sheets and presenting the same to the writing mechanism of said typewriter when said carrier is in writing position, and a dog on said carriage adapted to engage the notch in said rail and lock said carriage against movement, said dog being engaged and released by said carrier when the latter is moved into writing position.
46. In a writing apparatus, the combination with a typewriter having a shift key, and type bars each provided with a plurality of type faces rendered alternatively operative by manipulation of said shift key, of a flat platen to receive the impression of said type bars, and a pair of guard strips disposed adjacent said platen at opposite sides of the writing line respectively.
47. In a typewriting mechanism, the combination with type bars and a platen to receive the impression of said type bars, of brackets for supporting the ends of said platen, said brackets being provided with apertures, a pair of plates disposed at the outer sides of said brackets and having lugs engaging said apertures, and a pair of parallel elastic guard strips connecting said plate and supported thereby in proximity to said platen.
48. The combination with a typewriter having a carriage, of a plurality of interchangeable carriers each adapted for attachment to said carriage and each provided with means for carrying a supply of work sheets and presenting the same to the writing mechanism of said typewriter, and a holder for said carriers movable to bring any desired carrier into position adjacent said typewriter carriage.
49. The combination with a typewriter having a carriage, of a plurality of interchangeable carriers each adapted for attachment to said carriage and each provided with means for carrying a supply of work sheets and presenting the same to the writing mechanism of said typewriter, a holder for said carriers movable to bring any desired carrier into position adjacent said carriage, and means for locking said carriage against movement until a carrier has been brought into writing position thereon.
50. The combination with a typewriter having a carriage, of a plurality of interchangeable carriers each adapted for attachment to said carriage and each provided with means for carrying a supply of work sheets and presenting the same to the writing mechanism of said typewriter, a holder for said carriers movable to bring any desired carrier into position adjacent said typewriter carriage, and means for accurately positioning said holder with respect to said carriage.
51. The combination with a typewriter having a carriage, of a plurality of interchangeable carriers each adapted for attachment to said carriage and each provided with means for carrying a supply of work sheets and presenting the same to the writing mechanism of said typewriter, a holder for said carriers movable to bring any desired carrier into position adjacent said carriage, and means for locking said carriers in said holder and for unlocking each carrier as it is brought into position adjacent said carriage.
52. The combination with a typewriter having a carriage, of a plurality of interchangeable carriers each adapted for attachment to said carriage and each provided with means for carrying a supply of work sheets and presenting the same to the writing mechanism of said typewriter, a holder for said carriers movable to bring any desired carrier into position adjacent said typewriter carriage, a plurality of dogs on said holder for locking the several carriers therein, and a fixed cam engaged by said dogs successively as said holder is moved to unlock each carrier as it is brought opposite said carriage.
53. The combination with a typewriter having a carriage, of a plurality of interchangeable carriers each adapted for attachment to said carriage and each provided with means for carrying a supply of work sheets

and presenting the same to the writing mechanism of said typewriter, a holder for said carriers movable to bring any desired carrier into position adjacent said carriage, 5 and means for locking said holder against movement when any carrier has been partly but not completely removed therefrom.

54. The combination with a typewriter having a carriage, of a plurality of interchangeable carriers each adapted for attachment to said carriage and each provided with means for carrying a supply of work sheets and presenting the same to the writing mechanism of said typewriter, a holder for 10 said carriers movable to bring any desired carrier into position adjacent said carriage, means for locking said carriers in said holder and for unlocking each carrier as it is brought into position adjacent said carriage, 15 and means for locking said holder against movement when any carrier has been partly but not completely removed therefrom.

55. The combination with a typewriter having a carriage, of a plurality of interchangeable carriers, each adapted for attachment to said carriage and each provided with means for carrying a supply of work sheets and presenting the same to the writing mechanism 20 of said typewriter, a holder for said carriers movable to bring any desired carrier into position adjacent said carriage, means for locking said carriers in said holder and for unlocking each carrier as it is brought into position adjacent said carriage, 25 means for locking said holder against movement when any carrier has been partly but not completely removed therefrom; and means for locking said carriage against 30 movement until a carrier has been brought into writing position thereon.

56. The combination with a typewriter having a carriage, of a plurality of interchangeable carriers each adapted for attachment to said carriage and each provided with means for carrying a supply of work sheets and presenting the same to writing mechanism of said typewriter, a holder for 40 said carriers, movable to bring any desired carrier into position adjacent said carriage, a guide for said holder provided with notches, a dog on said holder adapted to engage said notches and lock said holder against movement, a series of levers disposed 45 respectively with their ends in the paths of movement of the several carriers during the movement of the latter into and out of said holder, and a link connecting the several levers with said dog, whereby when any carrier 50 has been partly but not completely removed from said holder said dog will be caused to engage one of said notches and lock said holder against movement.

57. The combination with a typewriter 55 having a carriage, of a cabinet having means

for supporting said typewriter, a plurality of interchangeable carriers each adapted for attachment to said carriage and each provided with means for carrying a supply of work sheets and presenting the same to the writing mechanism of said typewriter, and a holder for said carriers movable into and out of said cabinet to bring any desired carrier into position adjacent said typewriter carriage.

58. The combination with a typewriter having a carriage, of a plurality of interchangeable carriers each adapted for attachment to said carriage and each provided with means for carrying a supply of work sheets and presenting the same to the writing mechanism of said typewriter, and an elevator having compartments to receive the several carriers, said elevator being vertically movable to bring any desired carrier 75 into position adjacent said typewriter carriage.

59. The combination with a cabinet having an opening in its top and a typewriter supported by said cabinet and having a carriage, of a plurality of interchangeable carriers each adapted for attachment to said carriage and each provided with means for carrying a supply of work sheets and presenting the same to the writing mechanism 90 of said typewriter, an elevator received within said cabinet and movable through said opening, said elevator having a plurality of compartments to receive said carriers respectively, and means for raising and lowering 95 said elevator to bring any desired carrier into position adjacent said typewriter carriage.

60. The combination with a cabinet having an opening in its top and a typewriter 105 supported by said cabinet and having a carriage, of a plurality of interchangeable carriers each adapted for attachment to said carriage and each provided with means for carrying a supply of work sheets and presenting the same to the writing mechanism of said typewriter, of an elevator received within said cabinet and movable through 110 said opening, said elevator having a plurality of compartments for said carriers respectively, a hand lever and connections for raising and lowering said elevator to bring any desired carrier into position adjacent said typewriter carriage, a treadle, and means controlled by said treadle for positioning said elevator with any of said carriers opposite said carriage.

61. The combination with a typewriter having a carriage provided with a pair of parallel rails disposed transverse to the direction of movement of said carriage, of a plurality of interchangeable carriers each provided with means for carrying a supply of work sheets and each movable on said rails into and out of writing position in 125 130

which said work sheets are presented to the writing mechanism of said typewriter, and a holder for said carriers having a plurality of pairs of rails for supporting said carriers respectively, said holder being movable to bring the several pairs of rails thereon successively into alignment with the rails on said carriage.

62. In a typewriter mechanism, the combination with type bars and a reciprocating mechanism, of a carrier having a substantially flat and vertical platen to receive the impression of said type bars, means for moving a work sheet across the face of said platen in either an upward or a downward

direction, and means for engaging the reciprocating mechanism of the typewriter.

63. In a typewriter mechanism, the combination with type bars and a reciprocating mechanism, of a carrier having a substantially flat and vertical platen to receive the impression of said type bars, means for moving a work sheet across the face of said platen in either an upward or a downward direction without moving said platen or changing its position relative to the said type bars, and means for engaging the reciprocating mechanism of the typewriter.

In testimony whereof I affix my signature,

CLIFFORD W. MARSH.
